(57) **CLAIM**

The ornamental design for a “toaster oven,” as shown and described.

DESCRIPTION

FIG. 1 is a top, front, and left side perspective view showing our new design for a toaster oven.

FIG. 2 is a front view of the toaster oven shown in FIG. 1.

FIG. 3 is a left side view of the toaster oven shown in FIG. 1.

FIG. 4 is a right side view of the toaster oven shown in FIG. 1.

FIG. 5 is a top view of the toaster oven shown in FIG. 1.

FIG. 6 is a bottom view of the toaster oven shown in FIG. 1; and,

FIG. 7 is a rear view of the toaster oven shown in FIG. 1.

The subject matter shown in dashed lines is for illustrative purposes and forms no part of the claimed design.
